CLAIM

The ornamental design for a combined bottle and stopper, as shown and described.

DESCRIPTION

FIG. 1 is a side elevation of a combined bottle and stopper showing my new design, the opposite side being the same in appearance;

FIG. 2 is a front elevation thereof, the rear elevation being the same in appearance;

FIG. 3 is a bottom front perspective view thereof;

FIG. 4 is a bottom, side perspective view thereof;

FIG. 5 is a top plan view thereof;

FIG. 6 is a bottom plan view thereof;

FIG. 7 is a side elevation of the stopper shown separately for purposes of clarity;

FIG. 8 is a top plan view of FIG. 7; and

FIG. 9 is a bottom plan view of FIG. 7.
